INSECT EXCLUDING MEANS FOR SLIDING WINDOWS

Floyd F. Golkowski, Cleveland, Ohio

Application November 3, 1944, Serial No. 561,682

4 Claims. (Cl. 160—290)

1

The principal object of this invention is to provide a simple and practicable protective screen mechanism for use in standard window sash and casing assemblies whereby selectively to apply protective screening across the opening presented when either sash is moved to open position or to leave the screening in concealed and protecting position when the sash members are so moved.

Various mechanisms of the type as outlined above are known, but the arrangements previously proposed have been so complicated as to prohibit their practical application to standard sliding type windows. The present arrangement does not require any alteration of the window sash and casing assembly beyond drilling of a few holes in the sash and, as a further feature, the arrangement enables application of standard storm sash to the windows without requiring material alteration of the casing or sash, even though part of the space normally occupied by the storm sash is used to accommodate a portion of the apparatus hereof. The screen installation does not have to be removed when the storm sash is applied. The above indicates further objects.

Additional objects of the invention include the provision of an improved casing and roller mechanism for supporting and protecting flexible woven screen of metal, plastic or the like and present a reinforced free edge of the screen in a definite and desirable position for engagement by screen pick-up mechanism of respective sash members; an improved arrangement for guiding the free edge of such screen; improved means for scrubbing or cleaning at least one face of the screen when the screen is unrolled to span the window openings; an improved weather-proofing arrangement for the various window members with which the mechanisms hereof are associated, and an improved screen supporting roller mounting including quickly attachable and detachable means for supporting the roller.

Other objects and features of the invention will become apparent from the following description with particular reference to the accompanying drawings, in which.

Fig. 1 is a front view of a window casing and sash assembly incorporating the invention;

Fig. 2 is a vertical sectional view of the window casing showing the sliding sash and storm sash in elevation;

Figs. 3 and 5 are relatively enlarged sectional views respectively of the upper and lower portion of the window casing and sash assembly,

2

the views being taken as indicated by upper and lower portions of the line 3—4 on Fig. 1;

Fig. 5 is a detail rear elevation of one end of the screen support and guide substantially as used for both the upper and lower sash screen mounting;

Fig. 6 is a vertical sectional assembly view of adjacent portions of the upper and lower window sash and sealing means in accordance herewith for the gap which occurs when the sash are moved relative to each other to open the window;

Fig. 7 is a fragmentary central sectional and elevational view of the screen roller; and

Fig. 8 is a detail cross sectional view of one portion of a screen guide as indicated by the line 8—3 on Fig. 1 and revolved clockwise 90°.

The window casing 1 is of the usual type having side casing portions 2 and 3, a lintel portion 4 and sill portion 5. The casing as usual provides inner parallel channel guides 7 and 8 for the upper and lower sash 10 and 12, respectively. At the top of the casing the lintel has the usual storm sash seat shoulder 13 formed partly by a rib 14, and the sides of the casing are similarly shouldered to receive the storm sash. In the present construction a casing 15 for the upper screen and roller assembly is supported adjacent the upper portion of the shoulder 13, 14 as shown by Figs. 2 and 3.

The lower roller and screen assembly is mounted on the sill 5 in a casing 16. Said casing 16 is disposed inwardly from the plane of the shoulder 13, 14 and substantially in the plane of the upper sash groove or guide 7. Both casings 15 and 16 are substantially alike in function, being dissimilar mainly in respect to weather sealing and mounting adaptation details.

Referring particularly to Figs. 1, 3 and 7, the casing 15 has substantially identical end walls 17 and 18, the upper, lower and forward edge portions of which join top, front and bottom walls for the casing, indicated respectively at 19, 20 and 21. The inner side of the casing so formed is substantially open except for an inwardly and upwardly extending flange assembly 22 formed preferably as an extension of the bottom wall 21. The casing 15 is preferably attached in position adjacent the shoulder 13, 14 by brackets 23 which may be secured against the outer face of the lintel portion of the window casing.

It will be clear from Fig. 1 that the vertical proportions of the casing 15 are such that the usual storm sash 25 is readily accommodated beneath the casing 15. The upper bar 25a of the storm sash (see Fig. 3) seats against a sealing

strip 26 adjacent the inwardly extending flange 22 of the casing as by a strip 27 attached to said flange on its inner side. The strip 27 has an additional function which will be described later. The top surface of the upper bar 25a of the storm sash lies against the lower wall 21 so as to establish, in cooperation with the sealing strip 26, a relatively tight joint.

The storm sash 25 provided as usual with protective panes 28, partially shown, is ordinarily supplied several inches longer than it needs to be in order to fit the windows for which built. An extra wide margin is usually provided at the bottom and for use with the present arrangement it is usually only necessary to cut off as much from the bottom of the storm sash as will make the upper and lower bars 25a and 25b of the storm sash approximately of the same height. In some cases, of course, small portions of the top bar 25a may have to be cut off in order to accommodate the casing 15.

The storm sash is secured to the window by suitable means such as hinges shown at 29, Fig. 1, and an appropriate catch device or hook (not shown) at the side of the window opposite the hinges.

Referring further to Figs. 3 and 7, the strip of screen wire or plastic strands 30 is secured at one edge as by solder, welding or an attaching strip at 31 to the cylindrical body 32 of a tube which forms the roller. The roller has at one end substantially the conventional spring and attachment head 33, 34, respectively, a non-circular tip 35 of the head being adapted to enter a complementary opening in one end wall of the casing 15 when the spring has been sufficiently wound up to hold the screen strip wrapped about the roller. As shown the inner end of the spring 33 is anchored as at 34 on a cross pin 35 of the roller body. At the opposite end of the roller is a spring biased plunger 36 slidably mounted in a suitable end wall 37 of the roller, the plunger having a tip or projection 38 bearing in a central opening of the end wall 37. A coil spring 39 reacts at one end against a shoulder 40 of the plunger and at the opposite end against a cross pin or rivet 41 in the roller body. The arrangement is such that after the non-circular end member 35 has been inserted into the complementary opening in one wall (17, for example) the plunger carrying end of the roller is then moved into proper position with the axis of the roller in line with the bearing opening of the other wall (e. g. 18) thus causing, first, retraction of the plunger and then release of the same to allow the projection 38 to enter the bearing opening. In other words, the projection is simply cammed back axially of the roller by the end wall 18 of the casing until the projection 38 is brought into alignment with the bearing opening and then the spring snaps the projection into said opening.

The free end of the screen strip 30 is mounted on a retaining and reinforcing bar 45 shown in Fig. 3 as a doubled strip of sheet metal embracing the end margin of the screen strip and secured to it as by solder, rivets or other means not shown. The doubled metal member is adequately stiff to impart substantial rigidity to the edge of the screen strip. Each end of the bar 45 carries upwardly and downwardly projecting leg portions 46 and 47 (one pair shown, see Fig. 5) each pair constituting a T-head 48 for the bar. The leg members 46 and 47 may be formed separately from the folded metal of the bar 45 or integral therewith. The T-heads 48 of the bar

5 operate as guide members for the supported screen edge in suitably formed channels at each side of the window frame. The channels of each pair (one pair for each sash) are identical except that one is right hand and the other left hand; hence only one of the four channels requires description.

As shown by Figs. 3 and 8, each guide channel comprises a pair of cooperating parallel guide elements 50 and 51 preferably made as separate Z-bar shaped strips of sheet metal having flange portions 52 and 53 which lie against each other and one of which, as shown, is extended forwardly at right angles to the plane of the guide channel to form a flange 54 for attachment to the adjacent window frame. The flange 54, as shown, is attached as by screws 55 to the adjacent vertical window casing rib 14a which operates with the upper rib 14 of the casing in forming the outer guide for the upper sash 10. Thus a channel trackway is formed at each side of the upper sash and extending substantially from the top of the frame downwardly nearly to the lower limit of the upper sash. The channels are made long enough so that the T-head guides 48 will not be moved out of the channels when the upper sash is fully lowered and carries the screen with it to span the opening above the upper sash.

30 As a weather stop and rattle dampening cushion at the front marginal face of each sash 10 and 12, strips 56 of sealing material such as felt are supported (see Fig. 8) behind each of the guide channel assemblies 50, 51 etc. The strips 56 may be held in position as by adhesive against the flange portions 52 of the channel forming elements so as to bear resiliently against the side margins of the sash.

35 The normal position for the free edge of the screen strip 30 is as shown by Fig. 3 closely behind the casing 15 and near the top of the window frame opening provided within the ribs 14, 14a. The upper legs 46 of the T-heads hold the edge bar of the screen in the initial withdrawn position by abutment with the rib 14 of the window casing. For enabling engagement of such free edge of the screen, the screen edge reinforcing bar 45 has fixed thereto, as by solder, a pair of depending sheet metal tongues 58, the short free portions of which below the bar 45 are substantially flat and apertured at 70 and the lower ends 59 of which are gradually curved outwardly as clearly shown in Fig. 3 to serve as camming abutments for a pair of screen pick-up and releasing plungers 60 carried on the sash bar 57. The plungers engage respective apertures 70 and are identical, hence only one will be described.

40 Each of the plungers 60 preferably comprises a cylindrical body 61 pressed into a smooth horizontal bore 62 in the sash bar 57 or otherwise secured tightly in said bore. The body has a centrally apertured end wall 63 through which a free end or pin portion 64 of the plunger slides. The opposite end of the body may be closed by a ring 66 the inner surface of which cooperates with the opening of the wall 63 to form adequate supporting bearing for the plunger. Reacting at opposite ends against the ring 66 and a shoulder 67 on the plunger is a coil spring 68. The spring thus urges the plunger in a direction to the left as shown by Fig. 3 until the shoulder 67 engages the wall 63 or a releasing head or knob 69 of the plunger engages the ring 66 as a stop. The abutment for the plunger however provided holds the pin 64 in proper position so as to be cammed

to the right by the portion 59 of the associated tongue 58 depending from the edge supporting bar 45 of the screen. Thus, when the upper sash is moved to bring the pin 64 into alignment with the opening 70 of the associated tongue 58 the pin drops into the opening and thereafter, if the upper sash is lowered, the screen will be unrolled and caused to span the opening above the upper sash.

In order to lower the upper sash without movement of the screen, the operator pulls both knobs 69 to release the plungers 60 from the tongues 58 and then may lower the sash by using the knobs as handles. The knobs, in case of the upper sash, project only a slight distance inwardly of the window in order that should the upper rail of the upper sash be moved downwardly or the upper rail of the lower sash moved upwardly far enough to cause the two rails to overlap, the knobs will clear the upper sash bar of the lower sash. On the lower sash there is no danger of such conflict of parts and the knobs can be of any size.

The arrangement for supporting the free screen edge adjacent the lower screen roller casing 16 is exactly the same as described above with reference to the upper screen support construction and hence will not be described in detail. The similar parts of both upper and lower assemblies are similarly numbered. The downwardly extending legs 47 of the T-heads 48 of the lower screen bar 45 engage the window sill to hold the upstanding tongues 58 of the lower screen in proper position so that the apertures thereof receive the projecting pick-up and releasing plunger pins 64 when the lower sash is fully lowered.

It should be noted that the amplitude of guiding surface between the T-heads of the bar 45 and the associated guiding channels 51 is sufficient so that should the operator release only one of the plungers, the other plunger will cause the screen to be lowered without danger of distorting or damaging the guide, T-heads or screen. Such release of only one plunger would only happen accidentally.

The guide flanges for the lower screen 30 are indicated at 50a and 51a but the construction generally is exactly the same as in the case of the guide flanges 50 and 51 of the upper frame construction.

In order to guide and simultaneously clean the face of the upper screen as the screen is drawn from the roll, the flange 22 and strip 27 of casing 15 support between them a scrubber strip 75 which may be formed conveniently as a doubled strip of plain or sponge rubber or felt, the overlapping margins of the scrubber strip being clamped between a flange portion of the strip 27 and the flange 22. A similar scrubber strip 76 is supported by an inner wall portion 77 of the casing 16 as in a folded metal strip 78 embracing the overlapped portions of the scrubber strip and secured in suitable fashion to the wall portion 77. Except for the difference in shape the casing 16 is essentially similar to the casing 15 described above having fully enclosed end and horizontally extending walls to protect the roll of screen. The wall portion 77 of the casing 16 lies sufficiently above the top surface of the sill 5 to enable the free edge of the lower screen strip 30 to pass around the scrubber and into secured engagement with the supporting and reinforcing bar 45 for the lower screen strip. The outer wall of the casing 16 is modified to the extent of providing a horizontal attaching flange 80 projecting forwardly from the wall 79 of the casing in position

to be fastened directly to the top surface of the window-sill as by screws 81. The flange 80 and adjacent portion of the wall 79 are upstruck at suitable intervals at 82 to provide drainage channels for water that may accumulate on the sill inwardly from the casing 16 and thus enter the casing. The lower walls of the drain channels are formed by the top surface of the sill 5.

It will be apparent from the construction shown that, assuming the storm sash is opened or removed, the screen pick-up and releasing plungers can be readily operated to move said plungers to screen releasing positions either from the inside or outside of the window. The openings 70 in the tongues 58 for the plunger pins 64 are large enough so that the pins can be pushed back by human fingers—i. e. without requiring a tool of any kind.

An important insect excluding feature of the construction as shown particularly by Fig. 6 is a strip 85 of flexible sealing material such as rubber mounted on the lower surface of the lower sash bar 86 of the upper sash 10. The strip may be secured for horizontal adjustment toward and away from the pane 87 of the lower sash as by a series of screws, one of which is indicated at 88, passing through the strip 85 and a reinforcing or back-up metal strip 89 and into the wood of the said lower sash bar 86. The strips 85 and 89 may both be slotted horizontally and in a direction perpendicular to the pane 87 to be engaged by the inner edge of the sealing strip so as to enable adjustment to fit different designs of windows. The lower sash bar 86 of the upper sash as shown in Fig. 6 has been moved downwardly from its normal position, thus leaving a gap between the sash bars 86 and 90 through which insects could normally pass. When the lower sash is fully lowered and the upper sash 40 fully raised, the sash bar 86 would be in horizontal alignment with the upper sash bar 90 of the lower sash as usual and thereupon the strip 85 would lie against the outer lower surface of the bar 90 as a full weatherproofing means between the adjacent portions of the two sashes when closed.

I claim:

1. The improvement in a sliding window sash and spring-roller-supported screen assembly of the type in which the sash carries manipulatable means for selective engagement and disengagement with a free edge portion of the screen, comprising the employment of a spring actuated latch plunger member mounted in a substantially horizontally extending bore in the sash frame for movement transversely to the principal plane of the sash frame, and having an end portion projecting from said plane, a co-operating latching member on such free edge portion of the screen, one of said members having a cam surface oblique to said plane for causing retraction of the plunger member as part of the latching operation, and means for guiding and supporting said free edge portion of the screen, when disengaged by the latch plunger, the latching member of the screen then being engaged by the plunger incident to the sash being slid to its normal closed position in the window.
2. The improvement in a sliding window sash, sash frame and spring-roller-supported screen assembly of the type in which the sash carries manipulatable means for selective engagement and disengagement with a free edge portion of the screen, comprising the employment of a spring actuated latching means mounted in a por-

tion of the sash frame near one horizontal edge of the frame for movement transversely to the principal plane of the sash frame, a screen reinforcing bar on such free edge portion of the screen, said bar incorporating a cooperating latch means, and one of said latch means having a cam surface oblique to said plane for causing retraction of the first mentioned latching means as part of the latching operation.

3. The arrangement according to claim 2 wherein the latch means on the bar comprises vertically extending legs on the bar free from the screen for engagement with the sash frame.

4. The arrangement according to claim 2 wherein abutment means are provided on the screen and extend endwise of the screen to a position relative to the latch means of the screen to engage, and are operative to engage, a horizontal portion of the sash frame and stop movement of the screen by the spring roller in a position in which the latch means of the screen is aligned for cooperation with the latching means of the sash when the sash is in closed position.

FLOYD F. GOLKOWSKI.
